UNITED STATES PATENT OFFICE.

ANDRÉ WALS, OF GLASGOW, SCOTLAND.

LADY'S HAT-PIN.

1,073,881.

Specification of Letters Patent. Patented Sept. 23, 1913.

Application filed August 15, 1911. Serial No. 644,089.

To all whom it may concern:

Be it known that I, ANDRÉ WALS, a subject of the King of Great Britain, residing at Glasgow, Scotland, have invented certain new and useful Improvements in Ladies' Hat-Pins, of which the following is a specification.

This invention relates to hat pins for securing ladies' hats in place on the head.

10 Under this invention the hat pin has a point which, when pushed through the hat, turns, or curls back of itself so that the point will not project outward and be liable to do injury.

15 I prefer to make the pin of tubular formation with a second pin or wire extending therethrough said second pin being provided, at one end, with a suitable handle, knob or the like and at the other end, with 20 a spring or flexible part which is so made or tempered that, when this part, which carries the point is pushed beyond the tubular part it curls or turns back of itself so as to reverse the point. The spring or flexible 25 part may be simply a flat, spiral or other spring to which a point is secured or on which it is made. If desired, the second pin or wire may be of spiral formation throughout.

30 Instead of having the inner part of the hat pin provided with a turning back portion the outer tubular part may be made to carry the point and to bend or curl back on a wire or pin, in its interior being pulled.

35 In this case the tubular part may be made of spiral formation.

In order that the invention may be clearly understood I have hereunto appended explanatory drawings which show, by way of 40 illustration or example, two modes of carrying out the invention.

On the said drawings, Figure 1 is a view of one form of hat pin shown ready for insertion into the hat. Fig. 2 is a view of the 45 same in section. Fig. 3 is a view of the same hat pin as it appears after insertion through the hat, its point being turned back. Fig. 4 is a part section and part outside view of another form of hat pin, shown ready for 50 insertion into the hat. Fig. 5 is a view of the same with its point turned back.

The hat pin shown at Figs. 1 to 3 has a tubular member *a* within which is fitted a steel or other suitable pin or wire *b* of 55 greater length than the member *a* and having, at one end, an ornamental or other

head *c* and, at the other a point *d*. The end of the wire *b* on which the point *d* is provided has a spring action being tempered so as to normally turn back as shown at 60 Fig. 3. It is held straight when drawn within the tubular member *a*. The point *d* is shown made with a reduced part *d*¹ adapted to fit into the end of the tubular member *a*.

65 In the form of hat pin shown at Figs. 4 and 5 the tubular member *a*¹ is formed out of a spirally wound wire which has a spring action at its end being suitably tempered. The point *d*² is secured on the end thereof 70 and tends to turn back as shown at Fig. 5 being only kept straight when the inner pin or wire *b*¹ is pushed thereinto. The pin or wire *b*¹ in this case has an ornamental or other head *c*¹, and the point *d*² has a reduced 75 part *d*³ adapted to fit in the end of the tubular member *a*¹.

80 As will be seen, after pushing the tube *a* (Fig. 1) through the hat, if the head *c* is pushed the end of the inner wire *b* will be pushed through the tube thereby allowing it, owing to its spring action, to turn back thus presenting the point to the hat instead of having it projecting outward as usual.

85 With the arrangement Figs. 4 and 5 the head *c*¹ is pushed so as to force the tube *a*¹ through the hat and thereafter on pulling back the head *c*¹ the end of the tube *a*¹ turns back so as to present the point inward.

Having now fully described my invention 90 what I claim and desire to secure by Letters Patent is:—

1. A hat-pin, comprising a pointed pin-member adapted to pass through the hat and having its pointed end-portion tempered to normally bend back upon itself, and means forming part of the pin structure for temporarily straightening such tempered portion so that it can be pushed through the hat. 100

2. A hat-pin, comprising a pointed pin-member adapted to pass through the hat and having its pointed end-portion tempered to normally bend back upon itself, and sliding means forming part of the pin structure carried by said pin for temporarily straightening such tempered portion so that it can be pushed through the hat. 105

3. A hat-pin, comprising a pointed pin-member adapted to pass through the hat and having its pointed end-portion tempered to normally bend back upon itself, 110

- and means forming part of the pin structure
slidable in relation to said pin to engage and
temporarily straighten such tempered portion
so that it can be passed through the hat.
- 5 4. A hat-pin, comprising a pointed pin-
member adapted to pass through the hat
and having its pointed end-portion tem-
pered to normally bend back upon itself,
and a member slidable in its relation to said
10 pin member and supported to form a part
of the pin-structure and engaging the tem-
pered end-portion to temporarily straighten
the same.
5. A hat-pin, comprising a pointed pin-
15 member adapted to pass through the hat
and having its pointed end-portion tem-
pered to normally bend back upon itself,
and a sheath slidable upon such pin-member
to straighten and support such tempered
20 portion.
6. A hat-pin, comprising a tubular sheath,
a pin slidable in such sheath and having its

outer end-portion tempered to normally
bend back upon itself, and a point upon the
end of said pin and formed with a reduced 25
inner portion adapted to fit into the outer
end of the sheath.

7. A lady's hat pin having the end-portion
thereof carrying the point tempered so
that when the pin is pushed through the hat 30
it turns back on itself and is reversed and
means whereby the pin is held straight when
being pushed through the hat.

8. A lady's hat pin having the part adja-
cent the point thereof tempered so that 35
when the pin is pushed through the hat the
tempered part turns back on itself and re-
verses the point.

In testimony whereof I affix my signature
in presence of two witnesses.

ANDRÉ WALS.
